UNITED STATES PATENT OFFICE

JOSEPH FELIX EDOUARD FOREST, OF JOLIETTE, QUEBEC, AND ALZEARD FLORANT JOANISSE, OF HAWKESBURY, ONTARIO, CANADA

RAIL JOINT

Application filed June 19, 1931. Serial No. 545,412.

The invention relates to rail joints, as described in the present specification and illustrated in the accompanying drawing that forms part of the same.

This invention consists essentially of the novel self-locking feature in a rail joint as pointed out in the claims for novelty, following a description containing an explanation in detail of the preferred construction.

The objects of the invention are to facilitate the laying of tracks by eliminating the use of plates and bolts; to construct a joint that will be quiet when trains pass over it; to provide a rail joint in which wear will be negligible to such an extent that periodical replacement of rails will be necessary at the minimum, and, generally to reduce the costs of production of special joints and increase the efficiency as well as facilitating the installation.

In the drawing, Figure 1 is a side elevation of a section of track showing the joint.

Figure 2 is a plan view of Figure 1.

Figure 3 is an enlarged sectional view taken on the line 3—3 Figure 2.

Figure 4 is a view of the underside of the rail showing the locking member.

Figure 5 is a detail view illustrating the method of assembling the joint.

And Figure 6 is a cross sectional view showing a modified form of the invention.

Like numerals of reference indicate corresponding parts in the various figures.

Referring to the drawing, two rails ends 15 and 16 of the meeting rails which are fastened to ties 17 and 18 by the spikes 19, are connected together at the oblique undercut and overcut ends forming the split 20.

The rail end 15 is formed with a tapered boss 21 fitting into a tapered cavity 22 in the rail end 16 thereby forming the supporting surfaces 23 and 24 in the head of the rail end 16 for the aligning tongue 25 from the centre of the head of the rail end 16, lower down in the web of the rail end 15 the squared boss 26 registers with the square cavity 27 and aligns the web in the base 28 of the rail 16, the tongue 29 projects into the recess 30 and aligns the base. This forms a boss 31 of irregular shape between the cavities 27 and

30 extending into the rail 15 from the rail end 16. The key 32 extends from the base of the rail end 15 and is recessed in the base of the rail end 16 from the underside, said recess having the transverse slots 33 and receiving the cross piece 34.

To assemble the track, the ends of the rails are elevated as shown in Figure 5. The key 32 is placed in the recess in the base of the rail end 15 and the rails are lowered to the ground. As they are lowered the rail ends swing together, the tapered boss 21 slides into the tapered cavity 22 and the bosses 26 and 29 fit into their corresponding cavities 27 and 30. It is of course necessary to allow sufficient clearance for expansion and contraction due to changes in temperature.

The result of the assembly of the rail ends is that the surfaces abutting one another insure a three to four point bearing and in no instance is there a perpendicular line of contact or a continuous oblique line, consequently the distribution of the load is so spread longitudinally as to forbid the upper end of the split to communicate with the lower end except through intermediate contact points forming actual bearings.

In operation, the joint will normally lie flat, the wheels of the rolling stock in passing over the joint have a continuous rail surface to travel upon, and by having this continuous surface, "clicking" of wheels over the joint will be eliminated. The joint itself will close at the top when the cars pass and will operate in this manner, when the wheels approach on rail 15, the weight of the car will tend to depress the rail slightly causing the boss 21 to press on the supporting surface 24 in turn depressing the end of the rail 16. When the train approaches on the other rail 16 the surface 23 will bear on the boss 21 and draw down the end of the rail 15. It is of course to be understood that this movement will be very slight and will in fact occur only when wear and expansion separate the ends of the rails and bring this self aligning feature into play.

While we have shown our joint in use with railroad tracks it may also be used to join bridge girders and other structural steel members designed or used to carry steady loads.

The load bearing on the upper surface of the girder will keep the joint closed at all times, and removal of the load will allow disconnecting of the joint if required.

5 What we claim is:—

1. In rail joints, comprising a pair of rail ends abutting one another, an oblique groove in one rail end and a tongue on the other rail end, cavities in said tongue, bosses formed in said groove to correspond with the cavities in said tongue and adapted to register with one another when the rail ends are together, and a locking member on one rail end engaging a recess in the other rail end for locking the rails together.
- 10 2. In rail joints, comprising a pair of rail ends abutting one another and forming an oblique split between the rails, a groove in one rail, irregular shaped bosses formed in said groove, a tongue on the other rail end and having cavities corresponding with the bosses in said groove and adapted to register with one another to form bearing surfaces from rail to rail, and means for locking said rail ends together.
- 15 3. In rail joints, comprising a pair of rail ends abutting one another and forming an oblique split between the rails, a groove in one rail end, irregular shaped bosses formed in said groove, a tongue on the other rail end and having cavities corresponding with the bosses in said groove and adapted to register with one another to form bearing surfaces from rail to rail, and a locking member on one rail end engaging a recess in the other rail end for locking the rails together.

Signed at Montreal, Canada, this 13th day of April 1931.
